 Hopkan Rivet Company, Inc., Pittsburgh, Pa.,
 a corporation of Pennsylvania

Application December 17, 1936, Serial No. 116,369

3 Claims. (Cl. 30—20)

This invention relates to an opener for containers such as cans, jars and bottles.

The object of the invention is to improve on devices of this character as known heretofore, and to provide an improved opener of simple construction which can be manufactured and sold at a relatively low cost and which is easy to manipulate and highly effective in performing its intended function.

10 In accordance with the invention, I provide a container opener device comprising a guide or supporting member having gripping jaws reciprocably mounted thereon. A shaft extending vertically of the guide or support member 15 carries a cutter bar at its lower end having a cutter thereon which, when rotated, is effective to cut out the top of a can. A handle on the shaft facilitates rotation of the cutter. Other uses and advantages of the device will 20 become apparent from the following detailed description.

A present preferred embodiment of the invention is illustrated in the accompanying drawings, although it is to be understood that changes 25 in the details there shown may be made within the scope of my broader claims. In the drawings:

Fig. 1 is a longitudinal sectional view through the complete structure, parts being shown in 30 elevation;

Fig. 2 is a bottom plan view; and line I—I of Fig. 2 indicates the plane on which the section of Fig. 1 is taken;

Fig. 3 is a side elevation illustrating the use 35 of the invention in removing screw top lids from jars;

Fig. 4 is a partial sectional view along the line IV—IV of Fig. 2; and

Figs. 5, 6 and 7 are perspective views of 40 details.

A supporting member or guide 10 (see Fig. 5) slidably receives the shanks 11 and 12 of gripping jaws 13 and 14 having depending skirts 15 provided with inturned serrated edges 16 adapted to engage the side wall of a can 17, as shown in Fig. 1, or of a screw-top lid 18 on a jar 19, as shown in Fig. 3. The jaws 13 and 14 also have upwardly and outwardly extending hoods 20 for a purpose which will appear later.

50 The inner end of the shank 12 has a down-turned lug 21. The support or guide 10 also has a down-turned lug indicated at 22. A screw shaft 23 is swiveled in the lug 22 and has right and left-hand threaded portions engaging respectively the lug 21 and the depending skirt of

the jaw 13. A handle 24 is provided on the shaft 23 whereby the latter may be manually rotated to close or open the jaws 13 and 14.

A vertical shaft 25 is journaled in the support or guide 10, the shanks 11 and 12 being 5 bifurcated to admit the reduced lower end of the shaft. At its upper end the shaft is provided with a handle 26 secured thereto by a pin 27. The lower end of the shaft is squared and thereby adapted to fit into a square hole 28 in 10 a hollow cutter bar 29 (see Fig. 7). A spacer sleeve 30 is disposed on the shaft 25 between the cutter bar and the guide.

A cutter 31 (see Fig. 6) has a shank 32 and a downturned cutting edge 33. The shank of 15 the cutter is slidably received in the bar 29, as best shown in Figs. 1, 2 and 4. A compression spring 34 normally urges the cutter to its outermost position relative to the bar.

The handle 26 and the shaft 25 are bored to 20 receive a center punch 35 extending downwardly through the bar 29, the shank 32 being slotted at 36 to admit the lower end of the punch. The punch may be retracted in the shaft 25 to the extent permitted by the pin 37.

A lug 38 is pressed inwardly from the skirt 25 of the jaw 13 to provide an abutment for the cutter 31. The blade 33 thereof is notched at 39 to receive the lug 38. The lug thereby prevents upward yielding of the cutter when the 30 blade is pressed downwardly through the top of a can.

The manner in which the device described is manipulated to open a can will probably be apparent, but a brief description will now be 35 given. The jaws 13 and 14 are first retracted by turning the handle 24 on the screw shaft 23. The punch 35 is retracted and the cutter 31 positioned by turning the handle 26 and pressing the cutter inwardly of the bar 29 against the pressure on the spring 34 until the notch 39 on the blade 33 engages the lug 38. The device is then placed over a can in about the manner given in Fig. 1, and the jaws closed to approximately the final gripping position. 40 The whole structure is then pressed down so that the blade 33 cuts through the can top. The punch 35 may then be advanced by thumb pressure on its head, whereby its point also penetrates the can top. The jaws are then 45 tightened up by manipulation of the handle 24. Manual rotation of the shaft 26 causes the cutter bar and the cutter itself to swing around the can top and cut it out cleanly. The punch 35 provides a center about which the cutter 50

and bar rotate. When the cutter has traversed nearly the entire periphery of the can top, it strikes the lug 38. The jaws 13, 14 may then be retracted by operating the handle 24 and the device removed from the can. Since the cutter did not make a complete revolution, the severed top will be supported by the uncut portion of the top, instead of falling down in the can. The edge of the top opposite the uncut 10 portion may then be easily raised by a lifting point 40 struck up from the jaw 14.

In addition to opening cans, such as shown in Fig. 1, the device is also useful for unscrewing lids from jars. As shown in Fig. 3, this may be 15 accomplished by shifting the cutter bar out of its normal position and gripping the lid adjacent its top with the jaws 13, 14. Great leverage can be applied to the lid through the handle 24 and, since the jaws engage the lid near its top, 20 they do not cause the side wall of the lid to grip the mouth of the jar tightly, as is the case of most lid-removing devices. The punch 35, of course, is retracted, as shown in Fig. 3, when removing screw-top lids.

25 The invention is characterized by numerous advantages over known devices. Its simplicity of construction and ease of manipulation have been mentioned. Further advantages include the fact that the hoods 20 on the jaws prevent the user 30 from being burned by escaping steam when opening a can, the contents of which have been heated. The device is also useful for lifting hot cans out of a pan of hot water, for example, without danger of painful burns. The cutter, being slidably mounted in the bar, adapts itself to various 35 sizes of cans. It effects a clean, quick cut with the exertion of comparatively little effort. By using a screw shaft having right and left-hand threads, the action of the jaws is very quick. 40 The lug 38 prevents the cutter from being forced upwardly when the device is pressed down on top

of a can. A lug 41 struck up from the shank 12 of the jaw 14 serves as means for removing bottle crowns.

Although I have illustrated and described herein but one preferred form of the invention, it will be understood that changes in the construction illustrated may be made within the scope of the appended claims.

I claim:

1. A can opener comprising a guide, a pair of 10 opposed gripping jaws having shanks disposed in overlapping relation extending through said guide and adapted to have sliding movement therein, a vertical shaft journaled in the guide, a center punch slideable in said shaft, a cutter 15 holder secured to said shaft and rotatable therewith, a cutter carried on said holder, and means for actuating both said jaws simultaneously.

2. A can opener comprising a guide, a pair of 20 opposed gripping jaws having shanks disposed in overlapping relation, extending through said guide and adapted to have sliding movement therein, a screw shaft for actuating both said jaws simultaneously, a vertical shaft journaled in the guide, a cutter bar at the lower end of 25 said shaft, a cutter slidably mounted on said bar for movement longitudinally thereof, means normally urging said cutter toward its outermost position relative to said bar, and a seat on one of said jaws adapted to be engaged by said cutter.

3. A can opener comprising a guide, a pair of 30 opposed gripping jaws having shanks disposed in overlapping relation, extending through said guide and adapted to have sliding movement therein, a screw shaft for actuating both said 35 jaws simultaneously, a vertical shaft journaled in the guide, a cutter bar at the lower end of said shaft, and a center punch slideable through said vertical shaft and cutter bar.

DAVID HOPPENSTAND. 40
